UNITED STATES PATENT OFFICE.

CHARLES O. GARDINER AND WILLIAM C. DOWNEY, OF SPRINGFIELD, OHIO,
ASSIGNORS TO P. P. MAST & CO., OF SAME PLACE.

CULTIVATOR.

SPECIFICATION forming part of Letters Patent No. 237,749, dated February 15, 1881.

Application filed June 28, 1880. (No model.)

To all whom it may concern:

Be it known that we, CHARLES O. GARDINER and WILLIAM C. DOWNEY, of Springfield, in the county of Clarke and State of Ohio, have 5 invented certain Improvements in Cultivators, of which the following is a specification.

This invention relates to that class of machines in which shovel-beams or drag-bars arranged to swing vertically and laterally are 10 coupled to and drawn by a wheeled frame, and more particularly to those machines in which springs are applied to lift or assist the attendant in lifting the beams when required.

The first feature of the invention consists in 15 improved details relating to the lifting-springs, designed more particularly as an improvement upon the machine for which Letters Patent were granted to James M. Elder, bearing date December 9, 1879, No. 222,391, to give a better 20 action and more perfect adjustment to the Elder springs.

Figure 1 is a side elevation of a machine having 25 our improvements embodied therein, one of the main wheels being removed in order to expose the other parts to view. Fig. 2 is a 30 perspective view, showing a portion of the frame and axle on one side of the machine with our devices applied thereto. Fig. 3 is a front elevation of one of the couplings. Fig. 4 is a vertical central cross-section of the same.

In its general construction the machine is 35 similar to those now in common use. It consists, mainly, of an arched frame or axle, A, having the draft-frame or tongue D applied 40 to its top, and having its lower ends turned outward to receive the main carrying-wheels B and the couplings C, by which the beams or drag-bars E are attached. The draft-frame is secured to the top of the arched frame or 45 axle by means of flanged plates F, which fit over and around the bend or angle in the axle and against the tongue or draft-frame, to which they are bolted. Each plate F is formed with a lip or flange, a', in one corner, as shown, 50 for the purpose of guiding and holding other parts hereinafter described. Each of the couplings or beam-connections C consists of three parts—viz., a sleeve or tube, a, mounted on the axle or journal, a head or block, b, mounted 55 on and around the sleeve, and a forked plate,

c, secured rigidly to the beam and connected with head b by means of a vertical pivot pin or bolt, d. The sleeve is provided with two external longitudinal ribs, as shown, and is mounted upon the axle or journal in such manner that it can rotate freely, but not move endwise thereon. At its inner end each sleeve has a rigid arm, e, which will be described in detail hereinafter. The head or block b is cast in one solid piece, with an opening through 60 which the sleeve and its ribs fit closely, as shown. This arrangement permits the head to be moved laterally upon the sleeve, but compels the two to rotate together. A screw, g, inserted through and threaded into the head 65 b, serves the double purpose of fixing the same in place at any desired point on the sleeve, and also of drawing the head and sleeve tightly together, so as to give the head a solid bearing and prevent play or lost motion between 70 the parts.

When the screw is employed the other parts may be used with good results in the shape in which they come from the mold, without being accurately finished or fitted together, and thus 75 the cost of construction may be reduced to a very low point.

On its forward side the head b has a lug or projection to enter the forked end of the plate c. Through this lug and the plate c the pivot-pin d is inserted. A screw, i, tapped into the rear side of the head b, bears upon the pin d and holds the same firmly in the head, so that the entire wear is thrown upon the two ends of the pin. By thus arranging the parts they 80 are caused to wear much longer and retain a closer fit than otherwise, for the reason that the wear is received on a larger or more extended surface than would be the case were the pin left free to turn at its middle in the 85 head.

It will be seen that the connection of the parts is such that the entire coupling turns about the axle as the beam rises and falls, and that any forward strain applied to the arm e 95 tends to elevate the beam. The upper end of the arm e is provided with a series of holes, g', arranged at different distances from the center, and also in different vertical planes, as indicated in the drawings.

An upright rod, *G*, is passed down loosely through the lip of plate *F*, and connected at its lower end to the arm *e* by means of a pivot-pin passing through one of the holes in the arm, as shown in the drawings. The rod *G* is provided near the lower end with a series of holes, *h*, a collar, *l*, and a pin, *m*, passed through one of the holes to sustain the collar. A spiral spring, *H*, surrounding the rod *G*, bears at one end against the plate *F* and at the other against the collar, thereby exerting a downward pressure on the rod and the arm *e*, and counterbalancing the weight of the beam to a greater or less extent, according to the strength of the spring and the adjustment of the parts. As the beam rises and the arm *e* swings forward the increased advantage which the spring gains by the approach of the arm toward a horizontal position compensates for the loss from decrease in the tension, and thus a substantially uniform lifting action is exerted upon the beam. As the beam descends to an operative position the rod is brought in line with the shaft or axle, and thus the beam is relieved from the lifting action when the shovels are in the ground.

By changing the connection forward and backward from one to another of the holes in the arm the beam may be subjected to a slight lifting strain when in operation, or subjected to a downward pressure after descending below a given point. By changing the elevation of the washer the force of the spring may be varied, and the lifting strain thereby increased or diminished, as may be required. The two adjustments described, being entirely independent of each other, permit the machine to be adapted for work under all circumstances and conditions.

40 The upper plate, *F*, is provided, as shown, with the special lip *a*, which forms an inexpensive and solid bearing for the spring.

We do not claim, broadly, a lifting-spring acting upon a beam; nor the combination of a

beam with an arm, rod, and spring; nor a 45 spring which serves both to raise and lower the beams; nor a lifting-spring which acts with increasing force as the beam rises. The construction of the coupling, aside from the arm on which the spring acts, constitutes a separate independent invention, and is not claimed herein; but

What we do claim is—

1. The cultivator-coupling having the rigid arm, with its upper end provided with the series of holes disposed in different vertical and horizontal planes, as described and shown. 55

2. The combination of the frame, the beam-coupling having the upright arm formed rigidly thereon, the spiral compression-spring, and the sliding and swinging rod, having one end seated loosely in the frame, and the other end pivoted to the upper end of the coupling-arm by an adjustable pivot, which permits the rod to be moved forward and backward in relation 60 to the arm. 65

3. The combination of the frame, the coupling having the rigid upright arm thereon, the rod, and the spring, the spring being adjustable in tension, and the rod adjustable forward and backward at its point of connection with the arm, substantially as described. 70

4. In combination with the axle, the draft-frame, and the beam-operating rod, the flanged plate *F*, constructed as described and shown, 75 with the lip or flange, whereby it is adapted to serve the double purpose of uniting the frame and axle and of holding the rod and its spring.

5. The combination of the parts *b c*, the connecting-pivot, and the screw *i*, applied to hold the pivot, as shown. 80
